[57] CLAIM

The ornamental design for a hose guide for a recreational vehicle, as shown and described.

DESCRIPTION

FIG. 1 is a perspective view of a hose guide for a recreational vehicle showing my new design;

FIG. 2 is a view of one end thereof;

FIG. 3 is a view of the other end thereof;

FIG. 4 is an elevational view of one side thereof;

FIG. 5 is an elevational view of the other side thereof;

FIG. 6 is a plan view of the top thereof; and,

FIG. 7 is a plan view of the bottom thereof.

The broken line showing of a hose is for illustrative purposes only and forms no part of the claimed design.
